Fig. 3

FIG. 1 is a front perspective view of a slide projector showing my new design;

FIG. 2 is a rear perspective view showing the side opposite that shown in FIG. 1; and

FIG. 3 is a perspective view showing the bottom of the projector.

The dominant features of my new design are shown in solid lines in the drawing. The broken line showing of a slide aperture in the top of the projector is for illustrative purposes only.

I claim:

The ornamental design for a slide projector, as shown and described.
